UNITED STATES PATENT OFFICE.

FREDERICK SELBY, OF CHESTER, PENNSYLVANIA, ASSIGNOR TO JAMES C. FENDER, OF SAME PLACE.

DESIGN FOR A SKEWBACK.

SPECIFICATION forming part of Design No. 30,565, dated April 18, 1899.

Application filed March 22, 1899. Serial No. 710,107. Term of patent 14 years.

To all whom it may concern:

Be it known that I, FREDERICK SELBY, a citizen of the United States, and a resident of Chester, Pennsylvania, have invented and produced a new and original Design for a Skewback, of which the following is a specification.

My design for a skewback is fully shown in the accompanying drawings, in which—

10 Figure 1 is a front elevation of the skewback. Fig. 2 is a cross-section of the same on the line $x\ x$, Fig. 1; and Fig. 3 is a perspective view of the skewback.

15 The essential features of my design for a skewback are the inclined front faces offset from each other, forming a ledge, and a rear face in a perpendicular plane having a lateral recess near the lower portion of the same.

A minor feature of the design is the groov-

ing of the upper inclined face of the skew- 20 back.

1 is the base of the skewback; 2 and 3, the upper and lower inclined front faces of the same; 4, the ledge between the two; 5, the perpendicular back; 6, the recess near the 25 lower end of the same, and 7 the grooves in the upper inclined face of the skewback.

I claim as my invention—

The design for a skewback, substantially as described and as shown in the accompany- 30 ing drawings.

In testimony whereof I have signed my name to this specification in the presence of two subscribing witnesses.

FREDERICK SELBY.
